(57) **CLAIM**

The ornamental design for an adjustable chemical hose support stand, as shown and described.

DESCRIPTION

FIG. 1 is a perspective elevational view of the instant invention.

FIG. 2 is a front view of the instant invention.

FIG. 3 is rear view of the instant invention.

FIG. 4 is an isometric side view of the instant invention.

FIG. 5 is an isometric side view of the instant invention.

FIG. 6 is a top/bird's eye view of the instant invention; and,

FIG. 7 is a bottom/worm's-eye view of the instant invention.
